(57) **CLAIM**

The ornamental design for a computer keyboard, as shown and described.

DESCRIPTION

FIG. 1 is a top perspective view of a computer keyboard showing my new design;

FIG. 2 is a left side elevational view thereof;

FIG. 3 is a right side elevational view thereof;

FIG. 4 is a front side elevational view thereof;

FIG. 5 is a rear side elevational view thereof;

FIG. 6 is a top plan view thereof;

FIG. 7 is a left side perspective view thereof;

FIG. 8 is a right side perspective view thereof; and,

FIG. 9 is another top perspective view.

The bottom of the computer keyboard is flat and unornamented.

The portions of the keyboard shown in broken lines form no part of the claimed design.
